A. R. LAYMAN.
MULE STOP MOTION.
APPLICATION FILED MAY 28, 1915.

1,225,660.

Patented May 8, 1917.

UNITED STATES PATENT OFFICE.

ARTHUR RANDOLPH LAYMAN, OF DOVER, NEW HAMPSHIRE.

MULE STOP-MOTION.

1,225,660.

Specification of Letters Patent.

Patented May 8, 1917.

Application filed May 28, 1915. Serial No. 30,974.

To all whom it may concern:

Be it known that I, ARTHUR R. LAYMAN, a citizen of the United States, residing at Dover, in the county of Strafford and State 5 of New Hampshire, have invented certain new and useful Improvements in Mule Stop-Motions; and I do hereby declare the following to be a full, clear, and exact description of the invention, such as will enable 10 others skilled in the art to which it appertains to make and use the same.

The invention relates to improvements in mule stop motion.

The object of the present invention is to 15 improve the construction of mule stop motion more especially that shown and described in an application filed by me August 26th, 1913, Serial #786,912 and to provide a simple, practical, and comparatively inexpensive construction adapted to eliminate 20 the mechanism for operating a draft clutch for connecting the draft scroll with the shaft on which it is mounted and capable of enabling the shipper lever to be instantly operated when either the upper or lower flight or stretch of the draft rope breaks or slackens whereby the driving belt will be thrown from the driving pulley to the loose pulley and the machine stopped.

With these and other objects in view the invention consists in the construction and novel combination and arrangement of parts hereinafter fully described, illustrated in the accompanying drawings and pointed 35 out in the claims hereto appended, it being understood that various changes in the form, proportion and minor details of construction may be resorted to without departing from the spirit or sacrificing any of the advantages of the invention.

In the drawing

Figure 1 is a perspective view of a stop motion constructed in accordance with this invention, and shown applied to a portion 45 of a spinning mule,

Fig. 2 is a detail sectional view illustrating the arrangement of the cam arm for tripping the device for actuating the shipper lever,

Fig. 3 is a detail sectional view on the line 3—3 of Fig. 2.

Like numerals of reference designate corresponding parts in the several figures of the drawing.

In the accompanying drawing in which is illustrated the preferred embodiment of the

invention, 1 designates a front transverse rock shaft journaled in suitable bearings 2 and provided at one end with a segment 3 or segmental arm having a grooved periphery and secured to one end of a chain 4 or other suitable flexible connection. The chain 4 extends under a guide roller 5 and around a vertically disposed guide roller or wheel 6 and is connected at its rear end to 65 the lower end of an upright shipper lever 7. The shipper lever 7 which is pivoted at a point intermediate of its ends at 8 on the frame 9 of a spinning mule is provided at 70 its upper end with a loop 10 adapted to receive a belt, not shown, and capable of shifting the same from a driving pulley 11 to a loose pulley 12.

The driving belt, not shown, is designed to be arranged in the usual manner and is 75 shiftable from the driving pulley 11 to the loose pulley 12 to start and stop the machine. The horizontal and vertical guide rollers or wheels 5 and 6 are mounted in suitable brackets and the front transverse rock 80 shaft 1 has disposed on it a coiled spring 14 secured at one end 13 to the floor or other fixed point and connected at its other end by a set collar 15 with the shaft 1 and adapted to be placed under tension when an arm 16 85 of the shaft is swung rearwardly to the position illustrated in Fig. 1 of the drawing. The arm 16 is maintained in this position while the machine is in operation by a latch 17 and is adapted to be released to permit the spring 90 14 to swing the arm 3 forward and actuates the shipper lever to stop the machine. The latch 17 which is mounted on a horizontal pivot 18 of a stand 19 is approximately L-shaped and one arm extends upwardly and 95 is provided with a hook 20 which engages over the upper end of the arm 16 as clearly shown in Fig. 2 of the drawing. The other arm 21 extends rearwardly and is provided with lateral projections 22 and 23 adapted 100 to be engaged by arms or levers 25 and 26 for oscillating the latch to trip the mechanism for actuating the shipper lever. The lever 25 which is pivotally mounted on the horizontal pin or pivot 18 extends rearwardly from the latter and is located above the lateral projection 22 and it is provided at its rear end with a laterally extending pivot 27 on which is mounted a pulley 28 arranged on the lower flight or stretch 29 of 105 a draft rope 30. The lever 25 is connected at a point intermediate of its ends with a

- contractile spring 31 and the latter is placed under tension when the pulley 28 is arranged on the said lower flight or stretch 29 of the draft rope whereby when the draft 5 rope brakes or slackens at the lower flight or stretch 29 the spring 31 will actuate the lever 25 and cause the same to withdraw the latch from engagement with the arm 16 of the front transverse rock shaft 1, to stop 10 the machine.
- The draft rope 30 passes over a draft scroll 32 and its upper flight or stretch 33 engages a pulley 34 of an arm 35 of a crank shaft 36 journaled in suitable bearings of 15 brackets 37' and provided at one end with a crank 37 having a pin 38 operating in a slot 39 of a rod 40. The rod 40 extends upwardly from an arm 41 of a lower rock shaft 42 and the crank shaft has disposed on 20 it a coiled spring 43 secured to the shaft at one of its ends by a set collar 44 and connected at its other end to one of the brackets 37' and placed under tension and held normally so by the upper flight or stretch of the 25 draft rope whereby when the said upper flight or stretch breaks or slackens the crank shaft will be released and its arm 35 will be swung rearwardly in the direction of the frame and its crank arm swung upwardly to 30 partially rotate the rock shaft 42. The rock shaft 42 is provided at one end with the said arm 41 and its other end has an arm 45 which is connected by a rod 46 with the arm 26. The arm 26 is mounted on a horizontal 35 pivot 47 and it is adapted to actuate the pivot 47 and it is adapted to actuate the latch lever 17. The arm 26 is provided with a cam 48 located above the lateral projection 23 and adapted to engage the same and withdraw the latch from engagement with 40 the arm 16 when the arm 26 is swung rearwardly. While a pair of bracket arms is shown in the accompanying drawing for mounting the crank shaft, any other suitable bearing may be of course provided for the 45 same.
- The latch is normally urged forwardly by a coiled spring 49 disposed on the pivot 18 and connected at one end with the latch and at the other end with the stand or bracket 50 19. The spring will yieldably maintain the latch in engagement with the arm 16 until the latch is positively released or tripped.
- It will be seen that the device is exceedingly simple and inexpensive in construction 55 and that when either the upper or lower flight of the draft rope breaks or slackens the shipper lever will be instantly operated to shift the belt from the fast to the loose pulley for stopping the machine. Also it 60 will be clear that the stop motion constitutes a safety device and is adapted to enable a workman or other person to throw the machine out of operation by simply disengaging the arm 16 from the latch and that a 65 workman may go beneath the machine or

otherwise operate on the same with perfect safety as it will be positively impossible for the machine to start while the arm 16 is disengaged from the latch.

What is claimed is:

1. The combination with means for operating a shipper lever including a shaft having an arm, a spring for automatically rotating the said shaft, a latch normally engaging the arm for holding the shaft 70 against rotation and the said means out of operation, and means adapted to be held normally against movement by the opposite flights of a draft rope, the last mentioned means when released being arranged to move 80 the latch out of engagement with the said arm to permit the said shaft to rotate.

2. The combination with mechanism for automatically operating a shipper lever including a spring actuated shaft having an 85 arm, a pivoted latch provided with means for engaging the arm to hold the shaft against rotation and the shipper lever against movement, a pair of separate levers arranged to engage the said latch to release 90 the arm and spaced means connected with the levers and held against movement by the opposite flights of a draft rope for actuating the said pair of levers to release the latch when the draft rope breaks.

3. The combination with mechanism for automatically actuating a shipper lever including a shaft having an arm, a spring for automatically rotating the said shaft, of a latch provided with means for engaging the 100 arm, a lever arranged to swing the latch out of engagement with the arm, a spring for actuating the lever, means for connecting the lever with one of the flights of the draft rope for holding the lever normally against movement, and automatically operable means normally maintained in an inoperative position by the other flight or stretch of the draft rope for actuating the latch to release the said arm.

4. The combination with means for automatically actuating a shipper lever including a rotary spring actuated shaft having an arm, a pivotally mounted latch provided with means for engaging the arm, a cam arranged to move the latch out of such engagement, a crank shaft provided with means for engaging one of the flights or stretches of a draft rope and having a crank arm, a spring for actuating the crank shaft, a rock shaft, 115 means for connecting the rock shaft with the cam, and a rod extending from the rock shaft and having an opening engaged by the said crank.

5. The combination of mechanism for automatically actuating a shipper lever including a spring actuated shaft provided with an arm, a pivotally mounted approximately L-shaped latch provided at one of its arms with a hook for engaging the said arm of 125

the said shaft for holding the shipper lever against movement, the other arm of the latch being provided with lateral projections, a cam arranged to engage one of the 5 projections and located at one side of the latch, a lever located at the other side of the latch and arranged to engage one of the said projections to trip the latch, said lever being provided with means for engaging one of 10 the flights or stretches of a draft rope and means connected with the cam for engaging the other flight or stretch of the draft rope.

6. The combination of mechanism for automatically actuating a shipper lever including a shaft having an inclined arm, an 15 approximately L-shaped latch having a pivot and fulcrumed at its angle, said latch being provided at one of its arms with a hook engaging the arm of the said shaft for holding 20 the shipper lever against movement, the other arm of the latch being provided with lateral projections extending from the op-

posite faces of the said latch, a pair of levers located at opposite sides of the latch, one of the levers being mounted on 25 the pivot of the latch and arranged to be engaged with one of the lateral projections, the other lever being provided with a cam arranged to engage the other lateral projection, a spring for actuating the 30 lever that is mounted on the pin of the latch, means carried by such lever for engaging the lower flight of a draft rope, a spring actuated crank shaft having an arm engaging the upper flight of the draft rope and 35 means for transmitting motion from the crank shaft to the lever having the cam.

In testimony whereof I affix my signature in presence of two witnesses.

ARTHUR RANDOLPH LAYMAN.
